FIG. 1

FIG. 2

FIG. 3

FIG. 4

FIG. 1 is an elevational view of the front panel of a smoke exhausting hood, embodying the design.

FIG. 2 is a top plan view of the same.

FIG. 3 is a side elevational view of the same.

FIG. 4 is an enlarged vertical, sectional view looking in the direction of line 4—4 on FIG. 1.

The stippled area of the panel in FIG. 1 indicates contrast. The undisclosed side is substantially the same in appearance as the side shown. The dominant features of our design reside in the portions shown in full lines.

We claim:

The ornamental design for a smoke exhausting hood, as shown and described.
